UNITED STATES PATENT OFFICE.

HARLEY A. W. HOWCOTT, OF NEW ORLEANS, LOUISIANA.

OIL-REFINING APPARATUS.

Application filed February 7, 1924. Serial No. 691,240.

This invention relates to an apparatus for breaking up the hydrocarbons boiling at a higher temperature into hydrocarbons boiling at a lower temperature, and is more particularly directed to the cracking of the heavier hydrocarbons for the production of the more volatile hydrocarbons such as gasoline and naphtha.

An object of the invention is the provision of a device composed of a battery of stills each still being composed of a plurality of horizontal cylinders, serving as preheaters, and interconnected with a vertical cylinder in which the actual cracking occurs, in such a manner that the separated lighter hydrocarbons may be drawn from the vertical cylinders, and compressed air, which has been introduced into the horizontal preheaters will be retained substantially in said preheaters.

A further object of the invention is the provision of a plurality of horizontal preheaters and a vertical cracking cylinder connected with said horizontal preheaters, with stirrers in said horizontal preheaters for maintaining the oils in said preheaters in a constant state of agitation and vertically reciprocated agitating elements in the vertical cracking cylinder for maintaining the hydrocarbons in said vertical cracking cylinder in a constant state of agitation.

This invention will be best understood from a consideration of the following detailed description, in view of the accompanying drawing forming a part of the specification; nevertheless it is to be understood that the invention is not confined to the apparatus described, being susceptible of such changes and modifications which shall define no material departure from the salient features of the invention as expressed in the appended claims.

In the drawings:

Figure 1 is an end view of the battery of still units.

Figure 2 is a longitudinal section of one of the units of the battery shown in Figure 1.

Figure 3 is a horizontal section taken along the line 3—3 of Figure 2.

Figure 4 is a vertical section showing the spring pressed valve for permitting the vapors of the lighter hydrocarbons to escape under a predetermined pressure.

Figure 5 is a plan view of one of the agitating blades located in the vertical boiler.

Figure 6 is a sectional view of the valve casing controlling the compressed air to the horizontal boilers.

Referring more particularly to the drawings, 1 designates a frame supporting the first unit of the battery while 2 designates a frame of less height for supporting a second unit of the battery at a lower level than the first unit whereby the products of the cracking process carried on in the first unit may be directly conveyed by gravity to the second unit and thence from the second unit to a third unit which is located at a lower level than the second unit, or in other words is placed upon the ground. Mounted upon the frame 1, frame 2 and the ground are a plurality of furnaces 3, 4 and 5, respectively. These furnaces are shown more particularly in section in Figure 2. The opposite ends of the furnaces are provided with doors 6 and 7 to permit the entrance of a workman for inspecting the burners 8, 9 and 10 which are connected with a pipe 11 for supplying gas, oil or other fuel to the burners. The burners may be regulated in a well known manner for varying the heating of the contents of the preheaters which are interconnected with the vertical cracking cylinder.

Mounted on the furnace 3 are a pair of preheaters 12 and 13 which are connected at their inner ends to a vertical cracking cylinder 14. The preheaters 12 and 13 may comprise a single horizontal preheater with the vertical cracking cylinder 14 passing through the center of said preheater and at right angles to the longitudinal axis of the preheater but for practical purposes instead of a single preheater a pair of preheaters are mounted in horizontal alignment and provided with flanges 15 at their inner ends which are secured in any well known manner to the wall of the cracking cylinder 14. It will be understood that the wall of the vertical cracking cylinder 14 separates the horizontal preheater 12 from the preheater 13. Nevertheless the horizontal preheaters are in communication with cracking cylinder 14 through a plurality of spaced openings 16 formed in the side wall of the vertical cracking cylinder and adjacent its bottom so that the oil from both horizontal preheaters may enter the vertical cracking cylinder 14. A shaft 17 is mounted for rotation along the longitudinal axis of the preheaters 12 and 13 and is driven by a steam turbine 18

located adjacent one end of the preheater 13. Stirrers in the form of propellers 19 and 20 are mounted in spaced relation within each of the horizontal preheaters on the 5 shaft 17 and the blades being so constructed as to drive liquid in the preheaters toward a paddle wheel 21 rigidly connected with the shaft 17 and located between the propellers 19 and 20. The paddle wheel 21 comprises a hub 22 having radiating spokes 23 provided with paddles at their outer ends for cooperating with the propellers 19 and 20 for thoroughly churning or maintaining the material within the horizontal preheaters 10 in a constant state of agitation.

The shaft 17 is provided with a pair of spaced cranks 24 and 25 within the vertical cracking cylinder 14 to which are connected reciprocating rods respectively 26 and 27. A 20 plurality of agitating discs 28 and 29 are mounted on each of the reciprocating rods 26 and 27 and, as shown in Figure 5, and each of these discs are provided with a plurality of spaced perforations 30 through which the 25 vapors of the oil, which has been cracked in the horizontal preheaters 12 and 13, is further agitated by the reciprocation of the paddles by means of the respective connecting rods 26 and 27 and the cranks 24 and 25. 30 The upper end of the rods 26 and 27 are slidably mounted in bearings 31 formed in a diametrically disposed bar 32. A standard 33 is connected at its upper end with a bar 32 and at its lower end to the center of the conically shaped bottom 35 of the vertical cracking cylinder.

A pipe 36 which is connected with a source of steam under pressure passes through the bottom of the preheaters 12 and 13 and vertical cracking cylinder 14 for aiding in increasing the temperature and if desired the pipe may be perforated for admitting live steam to the hydrocarbon in said cracking cylinder. Drains 38 are connected to the 40 lower ends of the preheaters and the vertical boiler for draining off the residue of the oil after the lighter hydrocarbons have been removed from the same. Each of the top walls of the preheaters 12 and 13 are provided with oil inlet conduits 39 which are connected with a source for directly supplying by gravity or, if necessary, under pressure, oil to the said preheaters. A compressed air dome 40 is in open communication with the 45 top of the preheaters 12 and 13. A pipe 41, which is in communication with the dome 40 by means of a short connection 42, is adapted to supply air under pressure to the dome and thus to the top of the preheaters 12 and 13.

60 The upper end of the vertical cracking cylinder 14 is cone-shaped, as shown at 42^a and through the apex of which is inserted an arm 43 of a T-pipe 44. The inner end of the branch arm 43 is provided with an enlargement 45 and below which is adapted to re-

ciprocate a valve 46 connected with a stem 47. The inner end of the stem is slideable in the perforated boss 48 and the valve is maintained in its lowermost position by means of a resilient spring 49, which is adapted to resist a certain degree of pressure within the cracking cylinder before the valve is operated and moved upwardly into the chamber 45 for permitting the vaporized lighter hydrocarbons to pass through the pipe 43 and into 70 the branches 50 and 51, of the pipe 44, which branches are connected with cooling coils 52. The coils are maintained at a low temperature by flowing water in the tank 53 or cool air may be blown directly onto the coils. 75 From the coils 52 extends a pipe 54 which forms the inlet conduit for the second unit of the battery. The second unit is constructed exactly like the first unit and is connected with the third unit by a pipe 55 in a 80 manner similar to the connection between the first two units of the battery. Each of the units are exactly alike in every respect except that the first unit is elevated by means of the frame 1. The second unit is carried by 85 the frame 2 and is lower than the first unit but higher than the third unit. Any number of units may be employed in this connection which may be desired or required in certain cases. The third unit, designated generally 90 by the numeral 56, has a pipe 57 which leads to a storage tank for collecting the lighter hydrocarbons.

When the coils 52 are cooled by water the pipes 58 and 59 are connected with the usual 100 water supply for supplying the cooling chamber 53 with water.

The operation of my device is as follows:

Oil is supplied to the preheaters 12 and 13 until the oil level is reached as indicated by 105 dotted lines in Figure 2. The burners 8, 9 and 10 are lighted and heat applied to the three stills. A greater flame may be employed at the burners 8 and 10 than at burner 9, or vice versa as the conditions of 110 the case may warrant. Compressed air is admitted through the domes 40 and is adapted to be churned into the heated oil by means of the paddle wheels 21 and the agitators 19 and 20. The blades of the agitators are set 115 at such an angle that they will throw the oil directly towards the paddle wheels 21 whereby the oil is thoroughly churned and mixed with the compressed air. This churning action co-acting with the heat creates a 120 foamy mass and this convective action brings the combined foam and oil under the influence of the perforated discs in the vertical branch of the still and is thereby subjected to the action of the disc plates 28 and 125 29 and under the eddying action created under and over the discs distends into film form the oil and foam and permits free disengagement of the vapors of the oil entangled 130 therein which, because of pressure condi-

tions, tend to remain associated with the liquid oil. This provision therefore effects a considerably greater yield of gasoline or other lighter hydrocarbons than would otherwise occur. Oil passes from the horizontal preheaters 12 and 13 through the openings 16 at the bottom of the cracking cylinder 14 and passes upwardly into cracking cylinder. The shaft 17, through the cranks 24 and 25, drives the agitators connected respectively with the reciprocating rods 26 and 27 and again thoroughly churns the mixture in the vertical cracking cylinder. The lighter hydrocarbons which have been vaporized gradually force the valve 46 rearwardly towards the chamber 45 when the pressure within the boiler 14 becomes sufficiently great to overcome the tension of the spring 49. The pipe 44 is connected to the condensing coils 52 by pipes 51 where the lighter hydrocarbons in the state of vapor are condensed in the coils 52 and through the pipes 54 are carried to the next succeeding unit of a battery of the cooperating horizontal preheaters and vertical cracking cylinder.

The openings 16 are sufficiently large to permit the free passage of the oil from the longitudinal preheaters to the vertical cracking cylinder and at the same time they are placed sufficiently below the level of the oil in the cracking cylinder in order to prevent the easy access of the compressed air to the cracking cylinder 14 from the preheaters 12 and 13. If desired or when required steam may be admitted with the compressed air through the domes 40.

The combined action of the fuel heat, compressed air, steam, propellers 19 and 20 and the paddle wheels 21 located respectively in the preheaters 12 and 13 and the combined action of the heat, steam and the rising and falling of the agitating discs in the vertical cracking cylinder 14 and in connection with the pressure maintained in the vertical cracking cylinder tends to thoroughly break up the molecules of the crude oil vapors for the production of the lighter hydrocarbons which are ultimately cooled in the vaporizing coils 52.

The valve casing 61 is employed in the pipe line 41 for compressed air for permitting the flow of the compressed air to the horizontal still domes 40 and since the flat valves 62 are of the check valve type they will prevent the flow of fluid from the horizontal preheaters to the pipes 41.

Upon the inner wall of the vertical cracking cylinder 14 and at the opening 16 at the lower end of said cracking cylinder, check valves 16' are provided which permit the flow of fluid from the horizontal preheaters to the vertical working cylinders but prevent the flow of fluid from the vertical cracking cylinders to the horizontal preheaters.

What I claim is:

1. In an apparatus for cracking oil, a still composed of a plurality of horizontal preheaters, a vertical cracking cylinder interconnected with the said preheaters below the oil level therein, stirrers in the preheaters, stirrers in the vertical cracking cylinder, means for heating the still, and means for admitting compressed air to the horizontal preheaters. 70

2. In an apparatus for cracking oil, a plurality of horizontal preheaters, a vertical cracking cylinder interconnected with the horizontal preheaters below the oil level therein, a shaft in the horizontal preheaters, a paddle wheel on the shaft, a pair of propellers located upon opposite sides of the paddle wheel with the blades of the propellers so arranged as to drive the oil in the said preheaters towards the paddle wheel, agitating discs connected with the shaft and adapted to be reciprocated longitudinally of the vertical cracking cylinder for maintaining the vapors in the said cracking cylinder in a constant state of agitation. 75 80 85

3. In a device for cracking oil, a still composed of a plurality of preheaters, a vertical cracking cylinder interconnected with the horizontal preheaters below the oil level in said preheaters, stirrers in the horizontal preheaters, stirrers in the vertical cracking cylinder, means for heating the entire still, means including ducts for admitting compressed air to the horizontal preheaters, and a steam pipe passing through said preheaters and the cracking cylinder for heating the contents of the still and for supplying live steam to the same. 90 95 100

4. In an apparatus for cracking oil, a still composed of a plurality of horizontal preheaters, a vertical cracking cylinder interconnected with the said horizontal preheaters below the oil level therein, stirrers in the horizontal preheaters, stirrers in the vertical cracking cylinder, means for heating the entire still, means for admitting compressed air to the preheaters, a steam pipe passing through the horizontal preheaters and the vertical cracking cylinder for heating the contents of the still, domes connected with the preheaters, and a conduit connected with the domes for supplying compressed air thereto. 105 110 115

5. In an oil cracking apparatus, a still composed of a plurality of horizontal preheaters, a vertical cracking cylinder connected at its lower end with said horizontal preheaters, a connection placing the preheaters in communication with each other, means for heating the preheaters and the vertical cracking cylinder, means for admitting compressed air to the preheaters, and means for agitating the contents of the still. 120 125

6. In an oil cracking apparatus, a still composed of a vertical cracking cylinder, horizontal preheaters located in horizontal align- 130

ment and secured to the lower end of the cracking cylinder, the walls of the cracking cylinder where connected to the adjacent end of the preheaters being provided with 5 openings for placing the preheaters in communication with the cracking cylinder and providing a direct communication between the preheaters through the lower ends of the cracking cylinder, burners for heating the 10 still and means connected with the cracking cylinder for carrying off the vaporized hydrocarbons.

7. In an oil cracking apparatus, a plurality of stills connected together, each still 15 comprising a pair of horizontal preheaters in axial alignment, a vertical cracking cylinder connected to the adjacent ends of the horizontal preheaters and separating said preheaters from each other, the lower ends 20 of the walls of the cracking cylinder having openings providing a direct communication between the preheaters and between the preheaters and cracking cylinder, agitating means in the preheaters and vertically reciprocating agitating means in the cracking cylinder, means for supplying the preheaters above the level of the liquid content 25 with compressed air, and means for withdrawing the vaporized hydrocarbons from 30 the top of the cracking cylinder.

8. In an oil cracking apparatus, a still composed of a vertical cracking cylinder and horizontal preheaters connected thereto, said preheaters being located in horizontal alignment 35 and secured to the lower end of the cracking cylinder, the walls of the said cracking cylinder where connected to the adjacent end of the preheaters being provided with openings for placing said preheaters in 40 communication with the cracking cylinder and providing a direct communication between the preheaters through the lower end of the cracking cylinder, burners for heating the still, means connected with the cracking cylinder for carrying off the vaporized hydrocarbons, and a valve for controlling the flow of said vaporized hydrocarbons from the cracking cylinder, and for maintaining the contents of said cracking cylinder under a predetermined pressure. 45

9. In an oil cracking apparatus, a still composed of a plurality of horizontal preheaters with a vertical cracking cylinder interconnected therewith below the oil level 50 of said preheaters, a shaft passing directly through the longitudinal axis of the pre-

heaters and through the cracking cylinder, a portion of the shaft within said cracking cylinder being provided with cranks, means adapted to be reciprocated for agitating the contents of the cracking cylinder connected with the cranks, a paddle wheel located in each preheater and rigidly connected with the shaft, propellers mounted upon opposite sides of the paddle wheel and adapted to force the liquid contents of the preheaters towards the paddle wheel. 60 65

10. In an apparatus for cracking oil, a still composed of a plurality of horizontal preheaters, a vertical cracking cylinder interconnected therewith below the oil level of said preheaters, a shaft passing directly through the longitudinal axis of the horizontal preheaters and through the cracking cylinder, the portion of the shaft within the cracking cylinder being provided with cranks, means adapted to be reciprocated for agitating the contents of the cracking cylinder connected with the cranks, a paddle wheel located in each preheater and rigidly connected with the shaft, propellers mounted upon opposite sides of the paddle wheel and adapted to force the liquid contents of the preheaters toward the paddle wheel, domes connected with each of the preheaters, means for supplying the domes and the upper portion of the horizontal preheaters with compressed air, and burners for heating the contents of the still. 70 75 80 85

11. In an apparatus for cracking oil, a still composed of a plurality of horizontal preheaters with a vertical cracking cylinder interconnected therewith below the oil level of said preheaters, a shaft passing directly through the longitudinal axis of the preheaters and through the cracking cylinder, the portion of the shaft within the cracking cylinder being provided with cranks, means adapted to be reciprocated for agitating the contents of the cracking cylinder connected to the cranks, a paddle wheel located in each preheater and rigidly connected with the shaft, propellers mounted upon opposite sides of the paddle wheel and adapted to force the liquid contents of said preheaters towards the paddle wheel, and means for withdrawing the vaporized hydrocarbons from the cracking cylinder, and means for maintaining a predetermined pressure within the cracking cylinder. 90 95 100 105
